LOOM AND METHOD OF WEAVING

Margaret Clark, New York, N. Y., assignor of one-fourth to Edgar F. Rebner, Riverdale, N. Y.

Substituted for abandoned application Serial No. 43,167, October 2, 1935. This application June 11, 1940, Serial No. 339,842

21 Claims. (Cl. 139—33)

This invention concerns an improved method of weaving, and a frame or loom facilitating the carrying out of the said method.

5 This is a substitution of abandoned application Serial No. 43,167, filed October 2, 1935.

Generally speaking, my invention concerns the elimination of the harness action in weaving, i. e. there is no mechanical shifting of groups of alternate warp for the purpose of providing converse sheds. Whereas in the old art harness action or motion provides various sheds in chronological order, I arrange a frame in such fashion, that two or more sheds are present at the same time, consecutively arranged one behind the other.

15 It is readily understood, how the inlay in the one shed, which is near the position of the finished goods, may be beaten into the said goods in the same manner, as it is ordinarily done in the weaving art.

20 The inlay in the second, other shed, as arranged in front of the said one shed, must however be lifted over the position of the said one shed in order to be beaten in.

More complex shed formations, as they are 25 known with three or more different shed positions, may be provided in line with my invention analogously, as readily understood by those acquainted with the weaving arts. Therefore this description of my invention may be limited to

30 the simplest weave, in which the prior art simply reverses the positions of the upper and lower warp threads of one shed in order to produce another shed. Under such circumstances one phase of my novel method of weaving may 35 therefore be described as follows:

I arrange warps so that consecutively, i. e. in the direction in which they proceed, alternate sheds are formed one behind the other. The woof is shot into the one shed and then beaten 40 into the goods. A woof is further shot through the second, other shed, is then carried from that position, over the position of the one, first shed—the said one shed disappearing momentarily during this operation—and is beaten in. Then we 45 repeat the operation, by again introducing the woof into the one, first shed and beating it in, etc.

This method of mine may be carried out by way 50 of a very simple device, like that of Fig. 1; it may be carried out in a more complicated hand frame which facilitates faster working, like that illustrated in Figs. 2, 3 and 4, or it may be executed on a large scale, in the manner of mechanical looms, as it will be well understood by those 55 acquainted with the art, after they have studied

the simpler arrangements of the figures of the drawings.

For the purpose of laying in the woof, I may use a hand shuttle or machine actuated shuttles, in the same manner in which they are used in the 5 general art of looms. But in the case of smaller devices of my invention, I may also use shuttles, which are substantially of a length which exceeds the width the bed of the frame or the loom, so that the inserted shuttle may be shifted 10 from the other or second shed over the position of the first shed, to the point where the goods are being built up, the shuttle is then pushed through and out on opposite side, and the woof is beaten in. 15

These are the major objects of my invention; in connection with my improvements a great number of other objects and results arise as a matter of course, which will be better understood in the light of the following description, 20 and in connection with the accompanying drawings, in which:

Fig. 1 is a perspective view of a frame, in which for purposes of perspicuity are shown only two warps, woofs and a shuttle for the woof thread. 25 The frame is longitudinally cross-sectioned.

Fig. 2 shows a modification in a side view, a cross-section.

Fig. 3 shows a corresponding rear elevation.

Fig. 4 is a detail view of the drum I use in 30 connection with the modifications of Figs. 2 and 3.

Figs. 5 and 6 are a cross-sectioned side view and the top view of a section of a modified drum, and with and without ends, respectively.

Figs. 7 and 8 show, in side and top views, an- 35 other modification of my invention, with and without ends, e. g. flat strips, respectively.

The section and direction of view of some figures is identified elsewhere by the numerals of such figure, dot-dash line of section and arrow. 40

Similar numerals refer to similar parts throughout the various views:

Fig. 1 shows a weaving frame 15, which is for instance struck-up from sheet metal, and in which the warp travels from the left to the right. 45 Two pairs of clamping rollers 11 and 12 to the left and 13 and 14 to the right, indicate means providing the necessary tension and guide the warp ends at the left where they feed into the frame; the rollers 13 and 14 are equivalent to the take-up means or beam receiving and feeding finished goods away from a loom. In each instance one or both of the two rollers of a pair may be made of rubber in order to exert the 50 55

desired grip upon the ends to the left and upon the finished goods to the right.

These rollers are mounted in the frame 15; they may be rotated, e. g. by handles on one side (not shown). The end A, which represents one of the groups of alternate warps, passes through a guide hole 24 over the top of the frame 15, substantially in a straight line. Another end B, which represents the second group of alternate warp threads, passes first below the frame, underneath a depression 16 in the frame 15, so that it is spaced at said depression as a lower warp from the then upper warp A, the second or other shed being formed at this point. It will then be noticed that the warp B, as it passes to the right, arises inside of an individual dome 17, and emerges near the top of said dome through an opening 18. The second warp B is now above the first warp A, and at this point the first shed 19 is formed.

The woof W emerges at 20 from the finished goods (not shown) and is then shot through the one first shed 19, emerging at 21. It is understood that this woof between 20 and 21 may readily be beaten to the right into the finished goods.

From 21 to 22, the woof passes through the other or second shed 25, being extended through the hollow formed by depression 16 in the frame 15. This section 21—22 of a woof may then be pulled (by hand or while on a long shuttle) over the top of the dome 17, lifting up the warp A, and it is then beaten into the goods to the right, whereupon the lifted warp A falls back between adjoining domes 17. The shuttle is exemplarily indicated at 23.

The device of Figs. 2, 3 and 4 operates upon exactly the same principle as that of Fig. 1. A piece of sheet metal 31 is bent up to form the bottom 32 and the two sides 33 and 34 of a frame. There are substantially circular recesses in the sides 33 and 34, which protrude inwardly and provide pivotal supports 35 for the sector drum 36. The sector drum has that name because a

45 slit 37 extends through the whole length thereof and provides the other (second) shed 25. The drum 36 may be angularly set because the recesses 38 in the pivot 35 engage the overlapping lips 39 struck down in drum 36 along slit 37. The sector drum 36 is normally secured in the position of Fig. 2, but may be also rotated between the pivots, and may also be removed from between the side flanges 33 and 34, when the said springy side flanges are pressed apart.

55 41 and 42 are beams, respectively supplying one of the groups of alternate warp threads A and B, whereas 43 is the take-up beam. All three of these beams may be suitably tensioned, e. g. by a hook spring 44, which alternately extends below and above the beams, thus tensioning each one of said beams. A rod 46 is superimposed upon the take-up beam 43 and is suspended in the ears 47, thus extending on one side parallel to said beam.

65 It is readily understood that the warp ends may be slung over the said rod 46 when they are mounted and arranged in the frame before operation is started. The free terminals of the warps may be inserted in holes 28 in the other beams.

70 A number of bushings 51 here take the place of the domes 17 of Fig. 1. Warps B are strung from the beam 42 through suitable openings 52 in drum 36, through the bushing 51 and from there to the take-up beam 43. Other openings 54 and 75 55 are provided in the drum 36 which provide the

necessary friction for the warp A as extended from beam 41 through said openings over slit 37 (as top warp threads of the second shed) past the bushing 51 (then forming the bottom warp threads of the first shed) to the take-up beam 5 43. At the beginning of the operation the beam 43 may be arranged in the top notches 56, and may be moved to the other notches 57 as work progresses until it is finally lodged in the position of Fig. 2. The beams may be manipulated 10 at their protruding ends 27 (knurl 29).

In order to permit orderly tightening of a woof laid into a shed by pulling the woof end or shuttle, i. e. in order to prevent disheveling of the fabric produced by such pull, it may be desirable to provide guides on the sides of the set of extended warps, and/or the resulting fabric. Such guides are indicated by the slightly angularly disposed wires 58, in Figs. 2, 3 and 4. These guides extend from a point near the last feeding 20 elements of the upper warps of the last shed; they are coextensive with the said warps for a certain distance and have free, unsupported ends 59, from which the finished goods slide off. The guides 58 are shown to be fastened upon the 25 drum 36, next to the shed 25 or the slit 37, and lead arcuately at 60 to a point slightly above the level of the nozzle of the feeding element of the upper warps of the second shed, i. e. the upper ends of the bushing 51, and extend from 30 there to their ends 59 as described above.

Thus the guides 58 serve at the same time to guide and lift the woof from the first shed 25 in slot 37 over the bushing 51 to the point where, they are beaten into the finished goods, thus 35 facilitating the beating in of the said woof, be it carried over and beaten in by itself or by way of a shuttle slid over the top of said guides 58. In a hand loom the warps may be forced ahead by the beating in operation, particularly when 40 a shuttle or a needle carrying the woof is used for beating in; but the advancement of the warp may also be caused otherwise, by rotating beam 43 for instance.

Only two guides 58 are shown in the drawings, 45 near the last bushing. But it is understood that there may be a plurality of such guides, or that they may be made adjustable, within the knowledge of the art, so that they may be placed near any bushings representing the outside limits of 50 the weave being produced.

The manner in which the supports of the warps may be arranged in my invention in order to provide consecutive sheds, is of course subject to great variations, as already indicated by 55 55 the vastly different modifications of Figs. 1, 3 and Fig. 7 hereinafter to be described. Nor is it necessary that the means separating the alternate warps of one of the groups of the last shed be superimposed upon the bed of the loom, as 60 they are by way of the domes or hubs 17 of Fig. 1, or by way of the bushings 51 of Figs. 2, 3 and 4. Channels or grooves may be sunk into the material of the bed, in order to provide guide means supporting the group of alternated warps 65 interposed between the elevated group of warps, as illustrated by Figs. 5 and 6.

Anybody versed in the mechanical arts readily understand, that the solid drum 61 of Figs. 5 and 6 may be mounted in a suitable support, in a 70 manner analogous to the drum 36 of Figs. 2, 3 and 4. Transverse grooves 63 and 64 in the drum or cylinder body provide clearance for the sheds 25 and 19 respectively. Normal to said grooves extend grooves 62, which accommodate 75

the alternate warps A of the one warp group. The two groups A and B of the warp extend through holes 65 and 66, in the drum 61, and may thus be suitably tensioned and retarded.

- 5 My novel weaving method recommends itself on account of the simplicity of the tools involved. But it also offers improved weaving and improved products of weaving. In some instance this method allows ready weaving of materials 10 which are ordinarily very difficult to weave. For instance in connection with a very fine thread, wire or end, there is less hazard—on account of reduced friction—that the woven material tears or breaks in the weaving operation. Where flat 15 ends are to be woven, e. g. braids, leather strips or flat wires, my method represents an unmistakable improvement over the prior art.

An extremely simple execution of this invention is shown in Figs. 7 and 8, and is here exemplarily applied to flat or strip material, such as the leather just mentioned. The sheet 71 of resilient material serves as a support, and is mounted by the flat head screws 72 upon a bracket 73, which may for instance be mounted upon a table. Corresponding, for instance, in width to the flat ends A, B and W of leather to be woven in this device, the sheet 71 is slit providing ultimately longer and shorter reeds or tongues 74 and 75. These tongues are shaped to support the warp ends of 30 the slit material in shed formation, forming sheds 25 and 19, through which the woof W is extended. The ends of the longer tongues 74 extend so far down, as to engage in the finished or woven material 77, and so as more particularly 35 to serve as a back stop, resting against the woof 78 just beaten in, and reacting against the tension which is exerted upon the warp by the weights 79 in a direction counter to the direction of travel of the warp. Smaller weights 18 engage 40 the warp to the front, but are greatly counteracted by the weights 79, so that the weights 79 pull the goods back, after they have been pulled to the front during the beating in operation of the woof W extended through shed 25. Pairs 45 of weights 79 and 80 may be attached to the U-shaped rods 81 and 82 respectively which are engaged in loops formed by the warp thread, by being extended back and forth through the weaving device.

50 Such advantages are primarily attributable to the basic departure of my invention, in accordance with which chronologically changing sheds of the prior art are replaced by sheds consecutively disposed in the warp direction.

55 Having thus described my invention by way of several examples, it is this last mentioned, novel departure which I desire to protect broadly together with improvements which are entailed in the broad application of the said basic 60 invention.

What I claim is:

1. Method of weaving, comprising mounting a multiplicity of groups of warps on supports holding said groups at one time in a formation of 65 successively different sheds, laying woofs into said sheds, and forming goods by successively moving said inlaid woofs between the warps into a position forward of said last shed while said supports remain undisturbed.
- 70 2. Method of weaving, comprising supporting a multiplicity of groups of warps, so that said groups successively form different sheds in the direction of the intended movement of said warps, laying woofs into said sheds, and forming goods 75 by moving said inlaid woofs between the warps

to a position to the front of the last shed, one of the groups of warps forming the last shed being lifted off its support by a woof thus moved from a front shed in the said direction.

3. Method of weaving, comprising supporting 5 two groups of warps in a relatively raised and lowered position, so that they form a first shed; and—alongside of said raised and lowered position—in a relatively lowered and raised position, so that they form a second shed alongside of 10 said first shed; inserting a woof into said first shed and beating it in between said groups in a direction away from said second shed; and inserting a second woof into said second shed and beating it into a position alongside of said first 15 shed by moving it through the position of the first shed above the highest point of said first shed.

4. Method of weaving, comprising supporting two groups of warps in a relatively raised and 20 lowered position, so that they form a first shed; and—alongside of said raised and lowered position—in a relatively lowered and raised position, so that they form a second shed alongside of said first shed; inserting a woof into said first shed 25 and beating it in between said groups in a direction away from said second shed; and inserting a woof into said second shed and beating it into a position alongside of said first woof by sliding it over the raised group of warps of the first 30 shed, the lowered group of warps of the first shed being momentarily lifted over the raised group of warps of the first group, before the second woof has been slid across and is beaten into the goods being formed. 35

5. A weaving frame, comprising take-up means for a plurality of groups of warps connected by a weave, means tensioning the free ends of said warps, said groups being crossed between said take-up and tensioning means, and shed forming 40 means fixedly mounted on said frame and relatively guiding said groups of warps in multiple shed formation.

6. In a device like a loom, a frame, and sets of warp supports fixedly attached to said frame 45 and relatively offset in parallel planes in order to guide different warps in various shed formations, one of said supports being swingable towards the other in combination with one shed formation. 50

7. In a device like a loom, a frame, and sets of warp supports relatively fixedly attached to said frame and relatively offset in parallel planes in order to guide different warps in various shed formations, one of said supports being resiliently 55 swingable away from the other in combination with one shed formation in order to release a woof from a shed formed between said sets by the offsetting.

8. In a device like a loom, a frame, sets of 60 warp supports relatively fixedly attached to said frame and permanently lifting different warps into various shed formations, and means tensioning different warps independent from each other in a direction opposite to their direction of progress through said device. 65

9. Method of weaving, comprising supporting by fixed rests a plurality of groups of warps so that said groups form consecutive sheds in the warp feed direction, tensioning each of said 70 groups against its feed direction, laying woofs into said sheds, and beating in said woofs by pulling them through the warps in the feed direction beyond the last shed in that direction.

10. Method of weaving, comprising supporting 75

- on relatively stationary rests a plurality of groups of warps so that said groups form permanently allocated consecutive sheds in the warp feed direction, laying woofs into said sheds, and beating in said woofs over intervening rests into a fell behind the last shed formed by said warps in the warp feed direction and advancing the warps relatively to the sheds to the length of woven goods produced by said beating in.
10. 11. In a device like a loom, a frame, and sets of warp supports relatively fixedly attached to said frame and guiding different warps extended thereover in various shed formations, said warp supports supporting said warps in and between said sheds from below only, so that any warp may be freely lifted out of and above said sheds from the respective supporting means.
12. In a loom, fixed guide means for guiding a first warp along a path through said loom; and 10 fixed second guide means for guiding a second warp next to said first warp through said loom, said second means comprising a raised and a lowered element relatively spaced apart along said path, said elements serving to guide said second warp in multiple shed formation relatively to said path.
13. In a loom, fixed guide means for guiding a first warp along a path through said loom; and 20 fixed second guide means for guiding a second warp next to said first warp through said loom, said second means comprising a raised and a lowered element relatively spaced apart along said path, said elements serving to guide said second warp in permanent multiple shed formation relatively to said path.
14. In a loom, fixed guide means for guiding a first warp along a path through said loom; and 30 fixed second guide means for guiding a second warp next to said first warp through said loom, said second means comprising a raised and a lowered element relatively spaced apart along said path, said elements serving to guide said second warp in multiple shed formation at a minimum distance relatively to said path.
15. In a loom, fixed guide means for guiding a first warp along a path through said loom; and 35 fixed second guide means for guiding a second warp next to said first warp through said loom, said second means comprising a raised and a lowered element relatively spaced apart along said path, said elements serving to guide said second warp in multiple shed formation relatively to said path.
16. In a loom, fixed guide means for guiding a first warp along a path through said loom; and 40 fixed second guide means for guiding a second warp next to said first warp through said loom, said second means comprising a raised and a lowered element relatively spaced apart along said path, said elements serving to guide said second warp in multiple shed formation relatively to said path, one of said elements being notched in its transverse extent in order to provide a groove guiding said first warp.
17. In a loom, guide springs serving as rests for warp, some of said springs being shaped so that they are curved out of alignment with others, so that warp resting thereon is in shed formation relatively to warp resting on said others.
18. In a loom, a support, and guide springs 25 alignedly mounted on said support and serving as rests for warp, some of said springs being normally extended out of alignment with others, so that warp resting thereon is in shed formation relatively to warp resting on said others.
19. In a loom, a plate, and warp supporting reeds struck up from said plate in different directions and adapted to guide warps in shed formation.
20. In a loom, a resilient plate, and warp supporting reeds struck up from said plate in different directions and adapted to guide warps in shed formation.
21. In a loom, stationarily mounted shed forming means guiding different groups of warps at an angle with each other to a line at which said groups cross and thus form sheds on both sides of said line, and a frame supporting said means in a permanently fixed position.

MARGARET CLARK.
